UNITED STATES PATENT OFFICE.

FRANCIS HODGKINSON, OF SWARTHMORE, PENNSYLVANIA, ASSIGNOR TO WESTINGHOUSE ELECTRIC & MANUFACTURING COMPANY, A CORPORATION OF PENNSYLVANIA.

NOZZLE BLOCK.

Application filed December 21, 1923. Serial No. 682,118.

My invention relates to nozzle blocks as employed in fluid pressure turbines and it has for its object to provide a device of the character designated which may be readily formed in various capacities by simple machining operations and which, when assembled, shall be exceptionally rigid and durable in construction as demanded by the severe service imposed upon apparatus of this general nature.

In the accompanying drawing, Fig. 1 is a diagrammatic end view of a steam turbine, together with a steam chest and control valves, illustrating the general type of apparatus in which my improved nozzle block may be employed; Fig. 2 is a fragmentary view, partially in section, illustrating three blade rows as employed with a nozzle block of my improved construction; Fig. 3 is a cross-sectional view of an assembled nozzle block taken on the plane III—III of Fig. 2; Fig. 4 is an exploded view of my nozzle block, clearly illustrating the contour and relationship of the respective portions thereof; Fig. 5 is a side view, in elevation, of an assembled nozzle block embodying my invention; Fig. 6 is a plan view of a modified nozzle block for use with radial flow turbines; Fig. 7 is a side view of one-half the nozzle block shown in Fig. 6; Fig. 8 is a cross-sectional view of the half member shown in Fig. 7, taken on the plane VIII—VIII; and Fig. 9 is a plan view of a partition or septum member to be employed in defining the distinctive nozzle passages in the structure of Fig. 6.

In the construction of nozzle blocks as employed in fluid pressure turbines, it has been usual to employ rather complicated castings, involving considerable labor and expense to finish in proper form. Furthermore, different patterns, etc. have been necessary when constructing nozzle blocks of different capacities, it being well-known that turbines having the same frame and spindle are supplied with nozzle blocks having differing numbers of nozzle passages and different areas of nozzle passages in order to provide for different steam pressures, etc. and for different desired loads.

To maintain the patterns, etc. for supplying nozzle blocks of these various types has been a great expense.

In accordance with the present invention, I mill out complementary spaces in the faces of two forgings, said complementary spaces being adapted, when the members are fitted together, to define a nozzle space. Suitable partition or septum members are mounted between the two main members and serve to divide said main nozzle space into a plurality of nozzle passages. Hence, by the use of differing milling cuts, I may vary the size of the nozzle passages in the completed nozzle block and, furthermore, by forming more or less of said passages, I may increase or decrease the capacity of the block. All of said parts are firmly brazed or welded together after assembly, so as to form a unitary structure of great rigidity, as is demanded.

Referring to the drawing for a more detailed understanding of my invention, I show a turbine casing at 11 in Fig. 1 having a steam chest 12 mounted at the end thereof as is the usual practice. Steam is supplied to the turbine through a line 13, suitable branch lines 14—14 leading from the primary, secondary and tertiary control valves at 15 and the steam passing to suitable nozzle blocks disposed within the members 16—16, all as is well-known to those versed in the art.

Referring to Fig. 2, I show two rows of moving blades of the impulse type at 17—17, the first row of moving blades 18 and separated by a row of fixed blading 19.

A nozzle block 20, constructed in accordance with my invention, is disposed adjacent the first row of moving blades 18 and is segmental in shape as shown in Fig. 5, embracing a greater or less number of blades dependent upon the rating of the turbine and upon the properties of the steam which it is desired to employ. The nozzle block 20 embodies a plurality of nozzle passages 10—10 formed as hereinafter described to take steam from the steam chest and suitably expanding the same for impact upon the blades 18.

Referring more particularly to Figs. 4 and 5, the nozzle block 20 comprises an outer arc-shaped member 21 and an inner arc-shaped member 22 concentrically disposed with respect thereto, these two members together defining a nozzle space which

is divided into individual nozzle passages 36 by partition members shown more clearly at 23 in Fig. 4. As further shown in Fig. 4, the member 21 is milled at 24 to define a portion 5 of an inlet chamber, a throat portion 25 and a divergent portion 26. Similarly, the member 21 is milled to partially define an adjacent steam passage by the formation of a portion of a steam inlet 10 chamber at 27, a throat portion at 28 and a steam expanding portion 29. Similarly, at 15 30 I show portions of still another nozzle passage.

In like manner, the inner arc-shaped member 22 is milled away at 31 to define a steam inlet chamber portion complementary to that shown at 24, together with a throat portion 15 at 32 complementary with that shown at 25, and with a steam-expanding passage at 33 20 complementary with that at 26.

Similarly, the portion 34 of the member 22 is shaped to complete a steam inlet chamber by coaction with the portion 27 of the member 21, a throat portion 35 is complementary 25 with that shown at 28, and a steam-expanding passage, partially defined at 36, is complementary to that shown at 29.

Separating the partially defined steam 30 passages in the member 21 are slots 36'-36' and similarly separating the partially-formed nozzle passages in the member 22 are slots 37-37.

The partition, or septum, members 23 are 35 similar in configuration, preferably being formed of pressed steel, and embody a relatively wide portion 38 followed by a portion 39 narrowing in width and also tapering in thickness by virtue of being chamfered away, as shown at 40. Preferably 40 the partition is chamfered away to such an extent as to terminate in a sharp edge, short of the outer plane of the nozzle block, whereby the steam jets issuing from the respective jets merge into one stream for impact 45 upon the blading. At the head end of the portion 38 is formed a notch 41 surrounded by a flange 42 to assist in defining the entrance to the steam inlet chamber for the associated nozzle passage.

In assembling the parts thus shown to 50 build up the structure shown in Fig. 5, the member 22 is placed in concentric relation to the member 21 so that complementary portions of the milled surfaces thereof coact 55 to partially define steam passages. The partition members 23 are then slipped into the grooves 36'-37, one between each pair of adjacent steam passages, so as to completely define these passages.

It will be noted that the steam passages 60 thus defined are substantially rectangular in cross section, and as shown in Fig. 2, the members 23-23 lie in substantially parallel relationship. The portions 26 and 29 of the member 21 and portions 33 and

36 of the member 22, however, are so relieved or cut away as to cause a slight increase in the cross section of the nozzle passages toward the discharge end, thus permitting any desired pressure-velocity 70 conversion in the steam.

After the members 21, 22 and 23-23 have been assembled and properly lined up, they are firmly united into a unitary structure, as by welding or brazing. Preferably 75 I carry out this operation by placing small wires of copper or brass adjacent each joint to be established, together with suitable fluxing medium, and I then subject the entire structure to sufficiently high heat so 80 as to cause said copper or brass to flow through the adjacent joint, effecting a firm junction to impart strength, and also effectively preventing steam leakage. This operation may be carried out in an atmosphere 85 of hydrogen or of nitrogen, if desired, in order to prevent oxidation and insure a more reliable joint.

Fig. 3 is a cross sectional view of the completed nozzle block on the line III-III 90 of Fig. 2 and clearly shows the members 21 and 22 in juxtaposed relationship, together with the broad portion 38 of one member 23 and the narrow tapering portion 39 of an adjacent member 23, these partition members being shown as suitably received in the slots 36-36' and 37-37.

The structure described to this point constitutes a nozzle block of arc shape, having 100 nozzle passages transversely therethrough for projecting steam against a row of radial blading, but obviously the generic principles may be employed in conjunction with radial-flow blading by the use of a suitable arc-shaped nozzle block having steam passages 105 passing therethrough inclined to the radius thereof. Thus, in Fig. 6, I show a nozzle block made up of complementary halves 45 and 46 defining a nozzle space 47 therebetween, this nozzle space being sub-divided 110 by appropriate diaphragm members 48-48 into appropriate steam passages. In Fig. 7 I show the member 45 in side elevation, and it will be noted that the surface thereof is milled away as indicated in Fig. 8 to define 115 a portion of a steam passage at 49, together with a partition holding groove 50 (also shown in Fig. 7).

The partition members 48 are illustrated 120 in Fig. 9 and their function and method of insertion are apparent from the foregoing description.

Obviously the structure of Figs. 6, 7, 8 and 9 may be modified to discharge steam either inwardly or outwardly against a row of axially disposed blades as ordinarily employed in radial-flow turbines.

In the subjoined claims, I shall employ the term "joined by fusion" in a generic 130 sense to define a joining of members by

welding, brazing or otherwise, as may be found necessary or desirable in order to form a unitary structure of great strength and with freedom from leakage.

5 Thus, by forming two segments so as to abut against each other and by performing milling or gear cutting operations on their abutting faces, I am enabled to form nozzle passages symmetrical with respect to a 10 straight line tangent, for example, to the blade carrying wheel upon which the nozzle is to operate, resulting in a compact, durable and efficient structure.

It will be apparent from the foregoing 15 description that I may, with great facility, modify the number and shape of the nozzle passages in a desired nozzle block in order to suit the particular conditions all without carrying in stock a wide variety of patterns 20 or other expensive paraphernalia.

While I have shown my invention in but 25 two forms, it will be obvious to those skilled in the art that it is not so limited, but is susceptible of various other changes and modifications, without departing from the 30 spirit thereof, and I desire, therefore, that only such limitations shall be placed thereupon as are imposed by the prior art or as are specifically set forth in the appended 35 claims.

What I claim is:

1. A nozzle block for fluid pressure turbines embodying two abutting members defining a nozzle space and partition members 35 extending in substantially straight lines transversely of the two abutting members to define individual nozzles.

2. A nozzle block for fluid pressure turbines embodying two abutting members defining a nozzle space, slots extending in substantially straight lines transversely of the two abutting members, and substantially straight partition members located in the 40 slots to define individual nozzles.

45 3. An expanding nozzle for a fluid pressure turbine embodying two wall members diverging from each other and two partition members carried by said wall members and lying in parallel planes.

50 4. A nozzle block for fluid pressure turbines embodying two abutting wall members formed to present a series of converging diverging passages extending in substantially straight directions transversely of the 55 wall members, slots provided in the wall members between the passages, and partition members in the slots and together with the wall members defining individual nozzles.

5. An expanding nozzle for action against 60 a row of radial blading in a fluid pressure turbine comprising two wall members spaced apart in a radial direction and diverging, the one from the other, in the direction of fluid flow, and a pair of partition members 65 carried by said wall members so as to lie in

parallel planes and defining with said wall members a nozzle passage.

6. An expanding nozzle for action against a row of radial blading in a fluid pressure turbine comprising two wall members 70 spaced apart in a radial direction and diverging, the one from the other, in the direction of fluid flow, and each provided with a pair of slots flanking said diverging portions, respectively, and a pair of substantially straight parallel partition members 75 having their edges received in said slots and with said divergent members defining a nozzle passage.

7. A nozzle block for fluid pressure turbines adapted to discharge fluid against a row of radial blades and embodying an annular outer segment, an annular inner segment nesting therein, said segments being slotted in their abutting faces to define inner and outer nozzle walls, respectively, and partition members joining said segments to define distinct nozzle passages.

8. A nozzle block for fluid pressure turbines embodying two members abutting in a 90 surface normal to the plane of blade travel, complementary slots in the abutting faces of said members to define certain of the walls of the nozzle passages and septum members embraced between said abutting members 95 to define the respective nozzle passages.

9. A nozzle block for fluid pressure turbines adapted to discharge fluid against a row of radial blading and comprising an outer arc-shaped member having a portion 100 of its inner face cut away to form a portion of a nozzle space, and the wall of said cut-away portion being formed in a succession of nozzle passages diagonally disposed to the plane of the blade travel each defining a portion of an inlet chamber, a throat side and thereafter flaring outwardly toward the blades, an inner arc-shaped member having a complementary portion of its outer face cut away to form the remainder of said nozzle space and the wall of said cut-away portion being formed in a succession of diagonally disposed nozzle passages each defining a portion of an inlet chamber, a throat side 110 and thereafter flaring inwardly toward the blades, and a plurality of partition members joining said arc-shaped members between said successive surfaces, respectively, and forming therewith a plurality of expanding nozzles.

10. A nozzle block for fluid pressure turbines adapted to discharge fluid against a row of radial blading and comprising an outer arc-shaped member having a portion 115 of its inner face cut away to form a portion of a nozzle space and the wall of said cut-away portion being formed in a succession of nozzle passages diagonally disposed to the plane of blade travel each defining a portion of an inlet chamber, a throat side and 120 thereafter flaring inwardly toward the blades, and a plurality of partition members joining said arc-shaped members between said successive surfaces, respectively, and forming therewith a plurality of expanding nozzles.

125

- thereafter flaring outwardly toward the blades, an inner arc-shaped member having a complementary portion of its outer face cut away to form the remainder of said nozzle space and the wall of said cut-away portion being formed in a succession of diagonally disposed nozzle passages each defining a portion of an inlet chamber, a throat side and thereafter flaring inwardly toward the blades, each pair of adjacent surfaces being separated by a relatively deep, narrow slot in each of said arc-shaped members, and a plurality of partition members joining said arc-shaped members and having their edges received in said deep slots, respectively, said partition members with the adjacent formed surfaces defining a succession of expanding nozzles.
11. A nozzle block for a fluid pressure turbine provided with a succession of nozzle passages therethrough diagonally disposed to the plane of blade travel, the walls separating said nozzle passages extending substantially in a straight direction and parallel to each other and the remaining walls of said passages being formed to permit fluid expansion while passing therethrough.
12. A nozzle block for a fluid pressure turbine provided with a plurality of juxtaposed diagonal nozzle passages therethrough, each passage being of substantially rectangular cross-section and the separating walls extending substantially in a straight direction and parallel to each other, the remaining walls of said passages being formed to permit expansion of a fluid passing therethrough.
13. In a fluid pressure turbine, a fluid nozzle of substantially rectangular cross-section formed by two opposed members whose opposing faces are formed to provide an inlet chamber followed by a divergent passage and plane parallel septums joining said opposing faces.
14. A turbine nozzle comprising two abutting members with portions of their abutting faces cut away to partially define nozzle passages, and partition members embraced between said members and defining with said cut-away portions distinct nozzle passages, said partition members tapering to a sharp edge in the direction of fluid flow.
15. A turbine nozzle comprising two abutting members with portions of their abutting faces cut away to partially define nozzle passages, and partition members embraced between said members and defining with said cut-away portions distinct nozzle passages, said partition members tapering to a sharp edge in the direction of fluid flow and terminating short of the exit surface of fluid from said nozzle.

In testimony whereof, I have hereunto subscribed my name this tenth day of December 1923.

FRANCIS HODGKINSON.

Certificate of Correction.

It is hereby certified that in Letters Patent No. 1,612,436, granted December 28, 1926, upon the application of Francis Hodgkinson, of Swarthmore, Pennsylvania, for an improvement in "Nozzle Blocks," errors appear in the printed specification requiring correction as follows: Page 1, line 86, strike out the words "cent the first row of moving blades 18 and" and insert instead the words *and 18 respectively, said blade rows being*; page 2, line 83, for the misspelled word "juntion" read *junction*; and that the said Letters Patent should be read with these corrections therein that the same may conform to the record of the case in the Patent Office.

Signed and sealed this 1st day of February, A. D. 1927.

[**SEAL.**]

M. J. MOORE,
Acting Commissioner of Patents.
